FREDERICK W. MATHIEU, OF NEW YORK, N. Y., ASSIGNOR TO ROBERT PHILLIPS CO., INC., OF NEW YORK, N. Y., A CORPORATION OF NEW YORK

DESIGN FOR A LIGHTING FIXTURE

Application filed April 11, 1929. Serial No. 30,838. Term of patent 7 years.

To all whom it may concern:

Be it known that I, FREDERICK W. MATHIEU, a citizen of the United States, residing in the city, county, and State of New York, have invented a new, original, and ornamental Design for Lighting Fixtures, of which the following is a specification, reference being had to the accompanying drawing, forming part thereof.

Figure 1 is a side elevation of an electric lighting fixture; and

Figure 2 is a bottom plan view of the fixture.

In these drawings, it is to be understood that the panels 1 and lower plate 2 are formed of material permitting the transmission of light, and the upper ring member 3, as well as the upright arms 4 and the supporting spider 5, are formed of suitable material possessing sufficient strength to act as supporting elements.

I claim:

The ornamental design for a lighting fixture, as shown and described.

FREDERICK W. MATHIEU.
